UNITED STATES PATENT OFFICE

STACY B. HASELTINE, OF CHICAGO, ILLINOIS, ASSIGNOR TO W. H. MINER, INC., OF CHICAGO, ILLINOIS, A CORPORATION OF DELAWARE

CAR CONSTRUCTION

Application filed January 30, 1930. Serial No. 424,492.

This invention relates to improvements in car construction, and more particularly to combined locking and center pin means for connecting the body and truck bolsters of 5 railway cars.

One object of the invention is to provide an exceedingly simple combined locking and center pin construction, of rugged design for connecting the body and truck bolsters of 10 railway cars, wherein the pin member has shouldered engagement at opposite ends with the respective bolsters to prevent separation thereof, the shouldered engagement at one end of the pin being provided by a head member 15 on said pin, and the shouldered engagement with the other bolster being provided by a locking key extending through the pin and bearing on a member engaging the retaining shoulder of the corresponding bolster, the key 20 and cooperating bolster being so designed that the key may be readily applied.

A more specific object of the invention is to provide a combined locking and center pin construction of the character indicated in the 25 preceding paragraph, wherein the locking key is associated with the body bolster and is insertable through the top thereof to apply the same in locking engagement with the pin.

Other objects of the invention will more 30 clearly appear from the description and claims hereinafter following.

In the drawing, forming a part of this specification, Figure 1 is a top plan view of a portion of the body bolster of a railway car 35 illustrating my improvements in connection therewith. Figure 2 is a vertical, sectional view, through the body and truck bolsters of a railway car, corresponding substantially to the line 2-2 of Figure 1. And Figure 3 is a 40 vertical, sectional view of the upper part of the central portion of the body bolster illustrated in Figure 2, showing my improvements in connection therewith, the section being in a vertical plane at right angles to the plane of 45 the sectional view in Figure 2.

In said drawings, 10 designates the body bolster and 11 the truck bolster of a railway car. The body bolster is provided with the usual depending bearing projection 12, which 50 cooperates with a bearing seat 13 provided in

the top of a bearing block 14 mounted on the truck bolster. The bearing block 14 is seated within the usual pocket provided at the top of the truck bolster and is fixed against rotation with respect thereto. The body and truck 55 bolsters and the bearing block 14 are provided with the usual aligned center pin receiving openings 15, 16 and 17 respectively. The opening 17 of the bearing block is surrounded by an upstanding flange member 18 which engages within an opening provided in the bottom of the body bolster.

In carrying out my invention, I provide the body bolster with a relatively large pocket 19 which communicates with the opening 15 thereof. As clearly shown in Figure 1, the pocket is of considerably greater diameter than the opening 15, thereby providing a relatively wide annular retaining shoulder 20 at the inner end of said pocket. At one side 70 the wall of the pocket is cut away as indicated at 21, thereby providing a guide slot which has a curved bottom wall portion, as clearly shown in Figure 2.

The truck bolster is also provided with a 75 pocket, indicated by 22, disposed at the outer end of the pin receiving opening 16 of said bolster, the pocket being defined by the vertical connecting spaced webs 23-23 of said bolster.

My improved center pin construction proper 80 comprises a center pin member A, a retaining key B and a filler or supporting block C.

The center pin member A has a substantially 85 cylindrical shank portion 24, which extends through the pin receiving openings of the bolsters. At the lower end, the shank 24 is provided with a head member 25 which is disposed within the pocket 22 of the truck bolster and cooperates with the annular shoulder at the inner end of said pocket to prevent upward displacement of the pin A. Below the pin spaced slightly from the head thereof is a supporting plate or shelf member 26, adapted to support the pin when unlocked 90 from the body bolster. The plate member 26 comprises a horizontal section and down turned end portions 27-27 which are secured to the webs 23 of the bolster 11 by any suitable securing means, rivets being shown in the 100

present instance. At the upper end, the shank of the pin is provided with a transverse key receiving slot 28. As most clearly shown in Figure 2, the slot 28 has a substantially straight bottom end wall 29 and a curved upper end wall 30. The end wall 30 is preferably of convex formation as clearly illustrated in Figure 2.

The locking or retaining key B is preferably in the form of a relatively heavy plate-like member having a concave recess 31 at the upper end thereof which fits the convex bearing wall 30 at the upper end of the key receiving slot 28 of the pin, and a locking projection 32 at the bottom side thereof. The key B projects beyond opposite sides of the pin and the filler member C is interposed between the bottom of the key and the retaining shoulder 20 of the body bolster. As clearly shown in Figures 2 and 3, the filler member C is in the form of a ring surrounding the shank of the pin A. In order to finely adjust the spacing between the head at the bottom end of the pin and the cooperating shoulder 20 on the truck bolster, spacing shims or washers 33-33 may be interposed between the filler block or ring C and the retaining shoulder of the body bolster. Adjacent the shank receiving opening, the upper surface of the block C is cut away, as indicated at 34, to provide clearance for the locking projection and lower corners of the key member B while the parts are being assembled. As will be evident, when the parts are in the position shown in Figure 2, the key B is locked against removal, being confined between opposed side wall portions of the pocket and by the projection 32 engaged within the opening of the member C. As will be evident, the key can be removed only after the pin has been lifted to such an extent that the projection 32 is withdrawn from the opening in the member C and the lower edge portions at opposite sides of the key are disposed at such a height that they will enter the slot 21, the key being swung on the convex face 30.

The key member is preferably provided with an opening 35 in one side thereof within which a tool may be engaged in order to lift the key out of the pocket of the body bolster and remove the same from the slot of the pin.

In applying the center pin to the bolsters of a railway car, the pin member A is passed upwardly through the pocket of the truck bolster, entering the shank within the pin receiving openings of the two bolsters. The pin is then preferably temporarily supported in the position shown in Figure 2 by means of the shelf 26 which is secured to the webs of the truck bolster by rivets. The filler member C with the proper number of washers or shims interposed between the same and the shoulder of the body bolster is then placed in position about the shank of the pin mem-

ber A. The key B is then applied by inserting the same through the opening 21 in the side wall of the pocket 20. While the key is being assembled with the pin, the latter is slightly lifted so that the lower edges of the key will pass the outer wall of the opening 21 and the beveled surface 34 of the opening C, the upper end of the pin being provided with a transverse opening 36 for this purpose, any suitable tool being engaged within the opening to raise the pin. In entering the key B in the slot of the pin, the concave recessed portion at the upper end thereof is engaged with the convex wall at the upper end of the slot of the pin, the key being swung downwardly about the center of the curved surface 31 of the end wall of the slot into a position shown in Figure 2. After the key has been so positioned as to bring the projection 32 thereof in alignment with the opening in the ring C, the pin is permitted to drop so as to rest on the concave seat in the upper edge of key B, the locking projection 32 at this time engaging within the opening of the ring C. As will be evident, the key is thus held against accidental lateral displacement. When it is desired to separate the bolsters, the pin is lifted by a tool engaged with the opening 36 at the upper end of the shank thereof and the key swung to the right, as viewed in Figure 2, and withdrawn through the slot or opening 21 of the bolster 10, the key being manipulated by any suitable tool engaged within the opening 35 at the right hand side of said key. When the key has been removed, the pin drops and is supported by the shelf 26 and the body bolster may be lifted from the truck bolster. If it is desired to completely remove the pin, the shelf 26 may be detached and the pin dropped through the opening of the truck bolster.

I have herein shown and described what I now consider the preferred manner of carrying out my invention, but the same is merely illustrative and I contemplate all changes and modifications that come within the scope of the claims appended hereto.

I claim:

1. In car construction, the combination with body and truck bolsters having alined center pin receiving openings; of a locking pin extending through said openings and having a head at one end having shouldered engagement with one of said bolsters; a locking key extending through the other end of the pin; and means having shouldered engagement with the other bolster, said means also having shouldered engagement with the key and interlocking with said key to prevent accidental displacement of the key.

2. In car construction, the combination with body and truck bolsters having alined center pin openings, each bolster having a pocket at the outer end of its opening and a shoulder at the inner end of said pocket; of

a center pin member extending through said opening and having retaining means at the opposite ends thereof disposed within said pockets and having engagement with the corresponding shoulder, one of said means including a key extending through the corresponding end of the pin and the filler member interposed between the key and the shoulder of the corresponding bolster, said key being insertible through the outer end of the pocket of the corresponding bolster to apply the same to the key opening of the pin.

3. In car construction, the combination with body and truck bolsters having alined center pin receiving openings, each bolster having a pocket of larger diameter than said opening at the outer end of the opening, thereby providing a retaining shoulder at the inner end of the pocket; of a combined locking and center pin member extending through said openings and having means at one end thereof of having shouldered engagement with the shoulder of one of said bolsters, the other end of said pin being slotted; a key extending through the slot of the pin, said key being insertible through the open end of the pocket of the corresponding bolster, and said bolster being recessed adjacent said pocket to provide clearance for insertion of said key; and filler means in said pocket between the key and the shoulder of said bolster.

4. In car construction, the combination with body and truck bolsters having alined center pin receiving openings, each bolster having a pocket at the outer end of the opening thereof and the body bolster having a guide slot therein communicating with the pocket thereof and extending through the top of the bolster; of a combined locking center pin extending through said openings, said pin having a head at the lower end having shouldered engagement with the shoulder of the truck bolster, said pin having a transverse key receiving slot at the other end, said slot having a convex inner end wall at the upper end thereof; a key engaged within said slot, said key having a locking projection thereon, said key also having a concave seat cooperating with the convex wall of the slot, said key being assembled with the pin by insertion through said guide slot of the body bolster and being swingable on said convex wall of the key slot during assembling thereof; and a filler member within the pocket of the body bolster interposed between the key and the shoulder of said bolster, said filler member surrounding the pin, and also surrounding the locking projection of the key to prevent accidental displacement of the latter.

50 In witness that I claim the foregoing I have hereunto subscribed my name this 28th day of January, 1930.

STACY B. HASELTINE.
